UNITED STATES PATENT OFFICE.

FRANCIS MCF. BRINCKERHOFF, OF SUFFERN, NEW YORK, ASSIGNOR TO PRESSED STEEL CAR COMPANY, OF PITTSBURGH, PENNSYLVANIA, A CORPORATION OF NEW JERSEY.

SAFETY DEVICE FOR ARTICULATED CARS.

Application filed March 21, 1927. Serial No. 176,865.

This invention relates to transportation cars, particularly railway transportation cars of the articulated unit type in which the adjacent ends of two of the bodies of the car 5 are supported upon one truck and has for an object the provision of means for preventing accidental excessive movement of one of said bodies relative to the other and for preventing accidental excessive upward movement of one of said ends relative to the other and to the truck and will thus prevent the accidental separation of said bodies and will tend to maintain both of said ends in connected relation with the truck. 10

Another object of the invention is to provide means secured to one body of an articulated car unit adapted to cooperate with an adjacent body of the car unit to prevent accidental separation of said bodies. 15

A further object of the invention is to provide loop means adapted to cooperate with two adjacent bodies of an articulated car unit to prevent accidental separation of said bodies. 20

Other and other objects will be apparent from the following description.

Referring now to the drawings in which like reference characters refer to like parts, Fig. 1 is a plan view of a portion of a railway articulated car embodying the invention, a portion of the view being broken away to more clearly illustrate the invention; Fig. 2 is a side elevational view of the same, and Fig. 3 is a sectional view of the same taken on the line 3-3 of Fig. 1; Fig. 4 is a plan view of a portion of a railway articulated car embodying a modification of the invention, and Fig. 5 is a sectional view of the same taken on the line 5-5 of Fig. 4. 25

Referring now in detail to the drawings, the reference character 1 indicates one of the end portions of one body of a railway articulated car unit and 2 indicates one of the end portions of an adjacent body of the car unit, it being understood that the car unit may comprise two or any other desired number of bodies, and that the connection between any two adjacent bodies is substantially the same as hereinafter fully described. Depending downwardly from the end portion 1 is a bearing member 3 having a bearing surface 4 in the shape of a portion of a sphere, and depending downwardly from the end portion 2 of the adjacent body there is a similar member 3. The bearing surfaces 4

cooperate with a bearing surface 5 formed on a bearing member 6 on an adjacent truck 7. These bearing members forming a connection between the bodies and truck are described in detail in my pending application for U. S. Patent, Serial No. 176,864, filed March 21, 1927, for center bearing connection for articulated cars. 60

Around the outer portion of the bearing surface 5, the bearing member 6 has an upwardly extending flange 8 which is adapted to be engaged by the bearing portions 3 and by such engagement, under normal conditions, the bodies are held against excessive longitudinal or sidewise movement. In case of a collision or derailment the flange 8 may become broken so that one car body may become separated from the adjacent body, or one or both bodies may become separated from the truck and from each other and to prevent this I provide a loop 9 which cooperates with two adjacent bodies of the car unit in such a manner that the bodies will not be permitted to become separated from each other. In the present embodiment of the invention, this loop 9 comprises a metallic cable 10, the ends of which are secured to lugs 11 on the end portion 2 of one of the car bodies. Between its ends this loop passes around the bearing portions 3 of both cars and rests on horizontal lugs 12 formed on a curved web or stop 13 depending downwardly from the end portion of the other car body. The cable 10 for the greater portion of its length is encased in a tube 14 which is curved and is substantially concentric with the curve of the stop 13. This tube is rigid enough so that the loop will not change its shape under ordinary service conditions. There is a slight clearance provided between the loop 9 and the stop 13 which is for the purpose of permitting the bodies to swivel without any binding action taking place between the loop and the stop 13. 70

It will be noted that under ordinary service conditions the loop 9 rests on the lugs 12 and is spaced away from the stop 13, thus relative movement between the loop and the lugs 12 is permitted. Should a car equipped with the invention be derailed the center bearing portions of the two adjacent bodies may become separated from the truck bearing member, but the bodies will not become separated from each other due to the loop 9. 80

100

110

mounted on one body engaging the stop 13 on the other body. Should one body move accidentally an excessive distance relative to the other the loop 9 will engage the stop 13

6 and as the loop is in engagement with both bodies, further movement is retarded by the weight of the body that has not moved, thus the bearing portions of the bodies are kept from becoming separated from the truck 10 bearing.

In Figs. 4 and 5 a modification of the invention has been illustrated in which the ends of the loop 9 are brought closer together than in the preferred form and 15 these ends are secured or enclosed in a bracket 14 which in turn is secured to one car body at substantially the longitudinal center line thereof. Between its end this loop 9 passes around portions of the adjacent body and is loosely supported by suitable brackets. The operation of the loop is substantially the same as that just described in connection with Figs. 1 to 3 inclusive.

20 Having thus described the invention what I claim as new and desire to secure by Letters Patent is:-

1. A device for preventing the separation of the adjacent ends of two bodies of an articulated car comprising a member pivotally connected to one of said bodies and loosely engaging the other of said bodies.

2. A safety device for preventing the accidental separation of the adjacent ends of 35 two bodies of an articulated car comprising loop means secured to one of said bodies and loosely engaging the other of said bodies.

3. A safety device for preventing the accidental separation of the adjacent ends of 40 two bodies of an articulated car comprising flexible means secured to one of said bodies and loosely engaging the other of said bodies.

4. A safety device for preventing the accidental separation of the adjacent ends of 45 two bodies of an articulated car comprising a flexible member adapted to cooperate with both of said bodies.

5. A device for preventing the separation 50 of the adjacent ends of two bodies of an articulated car comprising a flexible member

secured to one of said bodies and loosely engaging the other of said bodies, and means for stiffening said flexible member.

6. A device for preventing the separation 55 of the adjacent ends of two bodies of an articulated car comprising a flexible connection adapted to cooperate with both of said bodies, and means for stiffening said flexible connection.

7. In an articulated car comprising a plurality of car bodies, a loop cooperating with the adjacent ends of two of said bodies for preventing separation of said ends, said loop being movable by one of said ends relative to 60 the other of said ends.

8. In an articulated car comprising a plurality of car bodies, a downwardly depending stop on one of said bodies, lugs on the adjacent end of an adjacent body, a member 70 extending around said stop and having its ends secured to said lugs, said member being adapted to engage said stop to prevent separation of said bodies.

9. In an articulated car comprising a plurality of car bodies, a curved stop on the end portion of one of said bodies, a safety loop on that adjacent end portion of an adjacent body adapted to engage said stop to prevent the accidental separation of said end portions.

10. In an articulated car comprising a plurality of car bodies, an articulation joint for the adjacent ends of two of said bodies, and a flexible safety member adapted to cooperate 85 with said ends to prevent the accidental separation of said bodies at said joint.

11. In an articulated car comprising a plurality of car bodies, an articulation joint for the adjacent ends of two of said bodies 90 and a safety loop member secured to one of said bodies adapted to loosely engage the other of said ends to prevent the accidental separation of said ends at said joint.

12. In an articulated car comprising a plurality of car bodies, an articulation joint for the adjacent ends of two of said bodies, and safety loop means for preventing the accidental separation of said ends.

In testimony whereof I affix my signature.

FRANCIS MCF. BRINCKERHOFF.
